US0D1103163S

(12) **United States Design Patent** (10) Patent No.: **US D1,103,163 S**
(45) Date of Patent: ** Nov. 25, 2025

(54) **ELECTRONIC DEVICE WITH A HINGE DISPLAY**

(71) Applicant: **Intel Corporation**, Santa Clara, CA (US)

(72) Inventors: **Surya Pratap Mishra**, Portland, OR (US); **Jeff Ku**, Taipei (TW)

(73) Assignee: **Intel Corporation**, Santa Clara, CA (US)

(**) Term: **15 Years**

(21) Appl. No.: **29/921,341**

(22) Filed: **Dec. 15, 2023**

(51) **LOC (15) Cl. 14-02**

(52) **U.S. Cl.**

USPC **D14/315**

(58) **Field of Classification Search**

USPC D14/315-318, 320, 327, 341, 345, 346, D14/439, 440, 444

(57) **CLAIM**

The ornamental design for an electronic device with a hinge display as shown and described.

DESCRIPTION

FIG. 1 is a right, front perspective view of an electronic device with a hinge display.

FIG. 2 is a front view of the electronic device of FIG. 1.

FIG. 3 is a top view of the electronic device of FIG. 1; and, FIG. 4 is a bottom view of the electronic device of FIG. 1. The features of the electronic device and the graphical user interface on the hinge display shown in broken lines form no part of the claimed design.

1 Claim, 4 Drawing Sheets
